TABLE ORNAMENT OR SIMILAR ARTICLE

Hans Hansen, San Francisco, Calif.

Application June 24, 1949, Serial No. 3,511

Term of patent 7 years

(Cl. D29—1)

To all whom it may concern:

Be it known that I, Hans Hansen, a citizen of the United States and a resident of the city and county of San Francisco, State of California, have invented a new, original, and ornamental Design for a Table Ornament or Similar Article, of which the following is a specification, reference being had to the accompanying drawing, forming a part hereof:

The single view is an elevational view of a table ornament, showing my new design.

The opposite side of the ornament from that shown in the single view is the same in appearance as the side shown.

I claim:

The ornamental design for a table ornament or similar article, as shown and described.

HANS HANSEN.
